[57] ABSTRACT

Simplified hydraulic forging machine having four hammers arranged substantially symmetrically, two of the hammers below and two above a horizontal plane passing through the centre (18) of forging, the hammers (12) cooperating with a hammer support (15), the two upper hammers (12s) being stationary, whereas the two lower hammers (12) are movable.

3 Claims, 1 Drawing Sheet

SIMPLIFIED HYDRAULIC FORGING MACHINE

This invention concerns a simplified hydraulic forging machine. To be more exact, the invention concerns a hydraulic forging machine comprising four hammers of which two are stationary and two are movable. All these hammers can be adjusted.

The known forging machines comprise four hammers, all of which are movable. Examples of forging machines of this type are given in EP 88108963 or in U.S. Pat. No. 4,745,793.

These forging machines are complex and extremely costly and require considerable energy for their working.

The present applicant has designed, embodied and tested the present invention so as to make a simpler and less costly forging machine which has a lower energy requirement for its working.

A simplified forging machine with four hammers according to the invention is set forth and characterised in the main claim, while the dependent claims describe variants of the idea of the solution.

According to the invention the forging machine comprises two stationary upper hammers, whereas its two lower hammers can move and perform the hammering action. The two stationary upper hammers act as anvils.

According to a variant the two stationary hammers comprise adjustment means for their better positioning and coordination.

The invention provides for the lower hammers to be movable since in this way the action of forward displacement of the product being forged is simplified.

The one single attached figure, which is given as a nonrestrictive example, shows a hydraulic forging machine **10** suitable to provide movable hammers **12** having the required movement.

The forging machine **10** comprises in each lower hammer assembly **11** a power ram **14**, a hammer **12**, a hammer support **15** and return-movement cylinder-piston actuation units, which are not shown in the figure. Connection and transmission means are included between the hammer support **15** and the ram **14**.

The hammer support **15** cooperates and forms one single body with a lever **16**.

The lower hammers **12** can be connected and actuated in any desired manner.

According to the invention the two upper hammers **12s** are stationary during the hammering action and therefore the lower hammers **12** alone can move.

According to the invention the upper hammers **12s** can be adjusted by an adjustment assembly **17** so that

they can be correctly positioned in relation to the forging centre **18**. The adjustment assembly **17** cooperates with return-movement actuation means, which in this particular example consist of a threaded abutment shaft **19**.

In the example shown the upper hammers **12s** too are anchored to a lever **16**.

The threaded abutment shaft **19** is included in cooperation with the hammer support **15** of the lever **16** and comprises rotation-prevention means **20**; it is displaced axially by a rotary sleeve **22** that rests against a bearing **23**.

The rotary sleeve **22** is actuated circumferentially by a worm **21** driven by a motor **13**.

The hammer support **15** cooperates with a return-movement cylinder-piston actuation unit, which is not shown in the figure.

I claim:

1. Simplified hydraulic forging machine having four hammers arranged substantially symmetrically, two of the hammers below and two above a horizontal plane passing through the center of forging, each the hammers being supported by a hammer support, the forging machine being characterized in that the two upper hammers during the forging operation are stationary, whereas the two lower hammers move to forge a work-piece during the forging operation.

2. Forging machine as claimed in claim 1, in which the upper stationary hammers can be adjusted by means of an adjustment assembly.

3. Forging machine as claimed in claim 1, further comprising two hydraulically operated power rams and connection and transmission means for connecting each hammer support of said two lower hammers to each of said two hydraulically operated power rams and for transmitting movement therebetween.
